W. E. WHITE

REENFORCING CHAIR

Filed Aug. 12, 1921

UNITED STATES PATENT OFFICE.

WILLIAM E. WHITE, OF CHICAGO, ILLINOIS.

REENFORCING CHAIR.

Application filed August 12, 1921. Serial No. 491,834.

To all whom it may concern:

Be it known that I, WILLIAM E. WHITE, a citizen of the United States, and resident of Chicago, in the county of Cook and State 5 of Illinois, have invented certain new and useful Improvements in a Reenforcing Chair, of which the following is a specification.

My invention relates to reenforcing devices and particularly to a novel chair or support for reenforcing rods.

One of the objects of my invention is to provide a device of extreme simplicity, which may be cheaply produced and possess 15 many if not all of the advantages of the more expensive and complicated devices. The desired result is secured by utilizing wire as the exclusive material for constructing the device and forming the wire sections 20 into two rectangularly disposed inverted U-shaped elements, the four legs being spaced ninety degrees apart. The transverse members of the U-shaped elements are welded at their intersection, and in one form of the 25 device I provide braces between the respective legs. In order to form a seat for a reenforcing rod I provide a third U-shaped member which is welded to one of the transverse parts of a U-shaped member. This 30 seat forming device may be composed of soft wire adapting it to be twisted over the top of a bar or it may be of stiff wire and constitute merely a seat without being twisted.

The invention will be more readily understood, by reference to the accompanying drawing, wherein,

Fig. 1 is an elevation of a chair constructed in accordance with my invention, a reenforcing bar being shown in place;

Fig. 2 is a view taken at right angles to that of Fig. 1;

Figs. 3 and 4 are similar views showing the form preferably used where a chair is intended to support and retain crossed bars;

Fig. 5 is a view of a modification intended for use in supporting the reinforcement for roads;

Fig. 6 is a view taken at right angles to that of Fig. 5; and

Fig. 7 is a sectional view on the line 7—7 of Fig. 5.

In the drawings it will be seen that the device comprises generally a pair of U-shaped members, each having legs 10 and a transverse element 11. One of the U-shaped

members is slightly shorter than the other, and the transverse member thereof underlies and is welded to the corresponding part of the longer member at their intersection as indicated at 12. A third U-shaped member 60, 13 is welded to the lower surface of a transverse member 11, the legs projecting upwardly and forming between them a seat for a reenforcing rod 14.

In the construction shown in Figs. 3 and 65 4 the parts are identical except in that the U-shaped wire 15 is made of softer steel and is intended to be twisted above crossed reenforcing rods 16, 17. Of course, a seat member of soft wire may be used for holding a single rod, or a stiff wire holding member may be used for retaining the crossed rods, this being wholly a matter of choice.

It will be noted that in the construction 75 described the legs 10 are flared somewhat, and are adapted to form a stable structure not likely to be displaced and comprising unusual strength for the weight of material utilized.

In the construction of Figs. 5, 6, and 7, the same U-shaped elements are employed, the legs 18 being considerably longer and preferably somewhat sharpened at their ends. They are welded at their intersection and, at a point intermediate their ends, are provided with brace rods 19 which are welded to the legs and to each other. These rods serve the double purpose of bracing the legs and of constituting limit stops for the 90 downward movement of the chair in earth. The chair is intended for use in supporting reenforcing rods 20 for concrete roadways. A U-shaped seat member 21, of soft or stiff wire, will be employed for holding the rods. 95

Obviously the construction is capable of much modification and I do not wish to be limited except as indicated in the appended claims. It will be apparent that if desired I may provide brace rods at the lower ends of the chair shown in Figs. 1 to 4 and, by lengthening the legs of this chair, such a construction so braced may be employed for road work instead of the form shown in Figs. 5 to 7 in which the ends of the chair enter the earth.

I claim:

1. In a reenforcing chair, the combination of a pair of staples rectangularly disposed and welded at the point of engagement be-

2
tween the transverse members of the staples, and means secured to the chair for forming a seat for a reenforcing rod.

2. In a device of the class described, the 5 combination of a pair of U-shaped members the transverse elements of which are welded at their intersection, and a third U-shaped element welded to one of said transverse members, the opening in the last-named U- 10 shaped member being upward to provide a seat for a reenforcing rod.

3. In a reenforcing chair, the combination of angularly disposed U-shaped members joined at their intersections and providing four legs, and transverse braces extending 15 between the legs at a point between the ends thereof, said braces being positioned to serve as limit stops for the downward movement of the chairs in earth.

Signed at Chicago, Illinois, this 3rd day 20 of August, 1921.

WILLIAM E. WHITE.
